BALL MILL

Adolf Dreyer, Potsdam, Germany

Application August 21, 1931, Serial No. 558,520
In Germany May 13, 1929

7 Claims. (Cl. 83—9)

The ball-mills used heretofore in the different branches of the cellulose lacquer- and paint industry are mostly provided with lining of silica bricks or hard burned porcelain, consisting of 5 single shaped stones, fastened together and to the inner-side of the drum by means of cement.

This kind of lining is imperfect, because, if ball-mills provided with such a lining or coating are used for wet grinding, disagreeable disturbances and interruptions in the working effect are caused even after a short time, as the employed cement is not sufficiently acid-resistant, to prevent the corrosion by the acid of the joints between the stones. The consequence is that the 15 grinding balls cut into the joints, thereby causing a loosening of the cement and the stones and consequently a more or less complete destruction of the lining.

My invention relates to improvements in such ball-mills thereby avoiding said inconveniences in a simple way. It has for its object to provide a drum of an acid-resistant and non-oxidizing steel which has been rolled to spring hardness, being preferably of a very small thickness. This 20 material will withstand successfully all tendency to corrosion and will give the possibility of an easy and rapid cleaning, so that the ball-mill can be used for several kinds of colors. Nevertheless, the apparatus is not much dearer to construct than the known mills.

A further object of my invention is to provide the drum with a wooden shell, preferably constructed by staves held together by means of displaceable span-rings. By means of this construction, it is possible to span the wooden shell to the 25 desired degree for resisting the strains arising in practice and thereby provide the necessary stability, to rapidly change the staves or the drum, if necessary, and to immediately note leaks from the drum, thereby avoiding loss of material.

The drum has a cover also of acid-resistant steel, said cover being so formed as to conform to the inner line of the drum, when set up. This cover may contain a valve device adapted for 30 taking samples as well as to release the overpressure arising from the grinding action. In order to prevent unauthorized parties from entirely screwing out the valve spindle from the cover, this spindle is according to my invention locked 35 against such removal by means of a pin.

With these and other objects in view the present invention consists in the combination and arrangement of parts, as will be hereinafter more fully described, shown in the accompanying drawing, and particularly pointed out in the ap-

pended claims, it being understood that changes in the form proportion, size and minor details may be made within the scope of the claims without departing from the spirit or sacrificing any of the advantages of the invention.

5

In the accompanying drawing,
Fig. 1 is a front view, partly in section,
Fig. 2 is a cross section.

The improved ball-mill forming the subject-matter of this application is adapted for use in connection with a drum *a* made of acid-resistant, non-oxidizing steel (e. g. of "Nirosta" steel, produced by Fried. Krupp, Essen). This has the advantage that the material of the drum can be made of very small thickness, whereby a great part of weight can be spared in comparison with the other known drums of mills. In order to secure the necessary stability of the thin drum, it is surrounded by a wooden shell *b* of pitchpine or the like consisting of single staves and held together by displaceable span-rings *c*, in order to prevent loss of material, if the cylinder of the drum after a long time has become worn. A changing of the drum *a* can, if necessary, take place in a short time in consequence of the extraordinary simple but solid fastening, whilst the cement for connecting the drum-linings of hard porcelain etc. requires several days to set.

10

The drum contains a manhole which is closed by a cover *d* of non-oxidizing material as well, which is secured by appropriate fixing means. This cover is so formed as to conform to the inner line of the drum, when set up. It contains fittings adapted for taking samples as well as to release the overpressure arising from the grinding action.

15

The fittings on the cover *d* mentioned above comprise a valve spindle *g* in a valve housing *e*, having a central channel *i* with an opening *h* to the interior of the drum and an opening *k* to the atmosphere. The valve spindle *g*, when 20 screwed in, shuts the opening *h* so that the drum is completely closed. By screwing out the spindle *g* the interior of the drum is brought into communication with the outer atmosphere by means of the openings *h* and *k* and the channel *i* between them.

25

For preventing unauthorized hands from completely screwing out and removing the valve spindle *g*, a pin *f* is provided in the spindle *g* within the housing *e*, which after the spindle *g* 30 has been screwed out to a certain extent bears against the housing *e*.

30

A similar valve fitting may be provided at the bottom of the drum, as shown at *m* in Fig. 1. When samples shall be taken out of the drum, 35

35

it will be advisable to turn it so that the cover *d* is brought to the underside of the drum. When the valve *g* is opened now, it will be necessary to open the valve *m*, now at the top of the drum, as well, for permitting air to enter into the drum. This valve *m* may be used for taking samples as well.

Having thus described my invention, what I claim is:

- 10 1. Ball-mill for grinding lacquers, chiefly of cellulose-ester lacquers, having a drum of acid-resistant and non-oxidizing steel rolled to spring hardness and of a very small thickness, a wooden shell, surrounding and supported by the drum, a cover of acid-resistant steel and a valve of the same material.
- 20 2. Ball-mill for grinding lacquers, chiefly of cellulose-ester lacquers, having a drum of acid-resistant and non-oxidizing steel rolled to spring hardness and of a very small thickness, a wooden shell, surrounding and supported by the drum, constructed by staves being held together by span-rings for the spanning and changing, a cover of acid-resistant steel and a valve of the same material.
- 25 3. A ball mill for grinding lacquers and the like, including a relatively light-weight drum and made of a relatively strong and complete sheet shell of acid-resistant steel simultaneously forming the lining and main frame of said drum, capable of withstanding the greater part of the interior stresses and expensive forces developed during the grinding operation, and means for stiffening and reinforcing the walls of said sheet

metal shell or frame including a wooden coating attached thereto and supported thereby.

4. A ball mill for grinding lacquers and the like, including a self-supporting metallic inner drum serving as a main frame for the mill and as a support for additional stiffening and reinforcing means arranged at the outer side of said metallic drum.

5 5. A ball mill for grinding lacquers and the like, including a self-supporting inner drum consisting of hard acid resisting steel, serving as a main frame for the mill and as a support for additional stiffening and reinforcing means arranged at the outer side of said metallic drum.

10 6. A ball mill for grinding lacquers and the like, including a self-supporting inner drum of hard acid-resisting steel serving as a main frame for the mill and as a support for a wooden shell surrounding the drum and constructed by staves held together by span-rings.

15 7. A rotatable ball or pebble mill for grinding lacquers and the like, adapted to contain grinding bodies together with the material to be ground comprising a self-supporting inner drum of hard and resistant steel serving both as a container 25 for said grinding bodies and materials and as the main frame for the mill and likewise serving as a support for a wooden shell surrounding the mill and constructed of wooden staves held upon the exterior of said mill by peripheral clamping 30 rings, which wood shell is wholly carried upon said mill and interposed between the same and said clamping rings.

ADOLF DREYER.
